MARINE PROPULSION UNITS

Peter Morton Hamlyn, Totney House, Kingsdown, Bath, Somerset, England; John Edwin Snelling, Woodlea House, Stockwood Vale, Keynsham, near Bristol, Somerset, England; and Bevan Graham Horstmann, 1 Fersfield, Perrymead, Bath, Somerset, England

Filed Dec. 18, 1961, Ser. No. 160,040
3 Claims. (Cl. 115—35)

This invention relates to marine propulsion units of the type adapted to be attached to the transom of a boat, and including a main casing containing a main driving shaft geared to drive a propeller shaft with the propeller mounted on the bottom of the casing, and a rudder also mounted on the casing astern of the propeller, said casing being supported by a transom bracket so that the whole unit is capable of tilting in a vertical plane should underwater obstacles be encountered when moving ahead. Marine propulsion units constructed according to the foregoing description are referred to herein as of "the type described."

While it is reasonably simple to provide for operating the rudder of such a unit from a rudder post mounted on the stern of the boat if the tilting action is omitted, it becomes a complicated matter when the unit is movable in relation to the rudder post. The object of the invention is to provide a simple and efficient device for transferring transom-located rudder post movements to the rudder without having to uncouple the steering arrangements when providing for tilting.

According to the invention in a marine propulsion unit of the type described the main casing houses a rudder mounting shaft projecting therefrom at its lower end which carries the rudder, and the unit is combined with a separate rudder post outside the main casing adapted to be mounted on the boat's transom, the post and mounting shaft each having an arm (the post arm and shaft arm respectively) projecting therefrom and turnable therewith, and over the main casing there is mounted, concentrically with the unit's axis of tilt, an arcuate frame of channel section the mounting of said arcuate frame being on a pivotal axis upstanding from the casing approximately radial of the frame from near its middle, the respective free ends of the post and shaft arms being freely located in the channel of said arcuate frame whereby movement of the arm from the said post is communicated to the mounting shaft arm.

By this construction the partial rotation of the rudder post causes the arcuate frame to perform a swivel movement rotating on the main casing by means of the engagement of the post arm with the frame, and the frame in turn causes the rudder mounting shaft to rotate through its shaft arm with which the frame is engaged. Notwithstanding this steering connection between the fixed axis rudder post located outside the main casing and the rudder mounting shaft, the unit comprising the main casing with its rudder, rudder mounting shaft and pivoted arcuate frame, may be freely tilted on its tilting axis because the arcuate frame will be carried with the main casing and describe a movement about its arcuate centre, whereupon its channel will run over the free end of the rudder post arm—which is non-movable in the vertical direction.

In order that the said invention may be readily understood an embodiment thereof will be described, by way of example, with the aid of the accompanying drawings in which:

FIGURE 1 is a perspective view of the unit attached to the transom of a waterborne vessel;

FIGURE 2 is a vertical section of the unit on a plane passing through the axis of the propeller shaft, and

FIGURES 3 and 4 are respectively sections on the lines

2

III—III and IV—IV of FIGURE 2 drawn to a larger scale.

The general view depicted in FIGURE 1 shows a marine propulsion unit embodying the invention and from this illustration there will be noted a main casing of a general T-shape designated as a whole by the numeral 1 having a top casing part 2 (the top bar of the T) and a depending part 3 (the leg of the T). This casing is mounted on a transom bracket 4 adapted to be secured to the transom 5 of a waterborne vessel 6. The transom bracket 4 has a pair of spaced apart parallel plate parts 7 constituting trunnion bearings between which the top part 2 of the main casing is mounted, being pivoted on a horizontal axis $x-y$ which coincides with the axis of the nut 8 and a shaft 14 (FIGURE 2). One of the said plate parts 7 is seen in FIGURE 1 the other being hidden behind a casing 17 also carried by the transom bracket 4. There is a vertical rudder post 9 rotatable in lugs 10 on the base plate part of the transom bracket 4, externally of the casing and within the tubular stern part 11 of the leg 3 of the T-shape main casing 1 there is rotatably mounted a rudder mounting shaft 15 (see FIGURE 2) operating the rudder 12. In the larger body part of the depending leg 3 of the main casing there is a sub-shaft 16 (see FIGURE 2) for the propeller 13. The main casing 1 can swing about the axis $x-y$ in the fore and aft direction when the unit encounters an obstacle.

Across the interior of the top 2 of the casing 1, and mounted at each end in suitable bearings is the aforesaid shaft 14 which is a tubular horizontal power-driven shaft, i.e. the main shaft of the unit, and this extends out of the casing at one end thereof into the aforesaid fixed casing 17. This contains a chain-sprocket arranged to drive the main shaft 14 through a suitable disc clutch. The latter is normally held in the engaged condition by springs adapted to press an end plate of the casing against the disc assembly, so that declutching can be effected by means of an internal push rod passing through the centre of the clutch assembly and into the main shaft. The fixed casing 17 containing the chain sprocket and clutch is continued through the transom 5 as indicated at 18 (FIGURE 1), and at the inboard end 19 there is mounted a second chain sprocket mounted in suitable bearings within the casing and formed with a central splined hole through which the driving shaft of an internal combustion engine can be passed for driving engagement. A driving chain connects the two sprockets so that the engine can transmit its power to the aforesaid main shaft 14 of the propulsion unit via the clutch just described. The construction of the shaft, push rod, clutch and general driving and control mechanism forms no part of the present invention, and details thereof can be seen in co-pending application No. 160,762 filed December 20, 1961.

The said main shaft 14 is adapted to drive the aforesaid sub-shaft 16 disposed at right-angles to the main shaft 14 and extending downwardly within the leg 3 of the T-shaped casing 1. It terminates near the foot of the casing in a bevel drive 20 to a propeller shaft 21 which extends out of the casing to drive the propeller 13.

Astern of the sub-shaft, the main casing 1 is formed downwardly from the cross-bar 2 of the T-shape along the leg 3 of the T with the aforesaid tubular housing 11 for the rudder mounting shaft 15 journaled therein at top and bottom and extending out at the bottom to carry the rudder 12.

Over the top of the main casing 1 there is pivotally mounted an arcuate frame 22 (roughly a semi-circle). The centre of the arc of this frame lies approximately on the axis of tilt $x-y$ of the main casing, and its pivotal axis $a-b$ passes through a swivel pin 23 upstanding from the casing and approximately radial of the frame extending from near the middle of its arcuate length to a point

near the axis of tilt. The said frame 22 is of channel section with the channel facing outwardly. The pivotal mounting arrangement on the axis $a-b$ is such that the frame may be turned independently of the casing 1 with its periphery moving on a path generating approximately a semi-sphere, and at the same time it may move with the casing 1 when the latter is tilted. This latter movement of the frame, assuming the same is lying in its central (fore-and-aft) position, is in a vertical plane normal to the axis $x-y$ of tilt.

As previously described, from the bracket plate 4 attached to the transom 5 there extends the pair of spaced parallel arms 7 constituting trunnion supports for the casing. The said bracket is also formed with the aforesaid spaced co-axial mounting lugs 10 and a socket 10a for the rudder post 9.

Splined on the rudder post is a sleeve 24 fixedly carrying an arm 25 extending radially outwards and then upwards towards the aforesaid arcuate frame 22. Its end terminates in a spherical knob 26 constituting a ball joint housed in a slipper 27 disposed within the channel of the frame.

On the aforesaid rudder mounting shaft 15 rotatably carried in the casing tubular part 11 and where it extends out of the top of its tubular housing 11, there is also splined an arm 28 similar to arm 25 carried by the rudder post 24, and this arm extends away astern of the main casing and its knobbed end 29 pivoted to a slider is located in the channel of the arcuate frame diametrically opposite the location of the end 26 of the rudder post arm 25.

Operation of the rudder post 25 will turn the frame 22 swivel-wise about the axis $a-b$ and as a result will cause the rudder mounting shaft 15 to turn by means of its arm 28. Should the unit swing upwardly away from the transom, the frame 22 will move with the casing in a clockwise direction with reference to FIGURE 2 and there will be relative sliding movement between it and the arm 25 of the rudder post.

The parts marked 30 comprise a locking arrangement associated with the tilting of the unit, and form no part of the present invention. Details thereof are described in co-pending application No. 160,041 filed December 18, 1961.

We claim:

1. Marine propulsion unit attachable to boats, including a main casing containing a main driving shaft geared to drive a propeller mounted on the bottom of the casing,

a rudder also mounted on the casing astern of the propeller, said casing being supported by a transom bracket in a manner whereby the unit is capable of tilting, a rudder mounting shaft housed within said casing and carrying the rudder, the unit being combined with a separate rudder post outside the main casing adapted to be mounted on a boat's transom, the post and mounting shaft each having an arm (the post arm and shaft arm respectively) projecting therefrom and turnable therewith, an arcuate frame of channel section mounted over the main casing concentric with the unit's axis of tilt, the mounting of said arcuate frame being on a pivotal axis upstanding from the casing approximately radial of the frame, the respective free ends of the post and shaft arms being freely located in the channel of said arcuate frame whereby movement of the arm from said post is communicated to the mounting shaft arm.

2. A marine propulsion unit as claimed in claim 1 in which the transom bracket by which the unit is supported is formed with lugs in which the rudder post is rotatable, the arm projecting from said post terminating in a slipper 25 slideable in the groove of the arcuate frame and connected to the arm by a ball joint whereby the arm can turn the frame about its pivot swivel-wise on the main casing, 25 while the unit can swing about its tilting axis causing relative sliding movement between the arcuate frame and the said slipper.

3. A marine propulsion unit according to claim 1 in which the main casing is of general T-shape having a top 30 casing part (the top bar of the T) and a depending part (the leg of the T), the latter part of the casing housing a sub-shaft geared to the main shaft and driving the propeller, and also having a tubular stern part in which is journaled the rudder mounting shaft extending out of the bottom to carry the rudder and out of the top to carry the shaft arm, the said shaft arm being fitted with a pivoted slider to engage in the groove of the arcuate frame.
